(57) **CLAIM**

The ornamental design for an inkjet printer with fixed sheet feeder and window access door, substantially as shown and described.

DESCRIPTION

FIG. 1 is a perspective view of an inkjet printer with fixed sheet feeder and window access door in accordance with the present invention;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and,

FIG. 7 is a right side elevational view thereof.

The broken lines in FIGS. 1-3 and 5 are for illustrative purposes only and form no part of the claimed design.
